UNITED STATES PATENT OFFICE.

GEORGES MALARD, OF TOURCOING, FRANCE.

WOOL-WASHING MACHINE.

989,622.

Specification of Letters Patent. Patented Apr. 18, 1911.

Application filed February 2, 1910. Serial No. 541,643.

To all whom it may concern:

Be it known that I, GEORGES MALARD, a citizen of the Republic of France, residing at Tourcoing, Nord, France, have invented 5 certain new and useful Improvements in Wool-Washing Machines, of which the following is a specification.

This invention relates to machines for washing wool, and has particular reference 10 to an apparatus which automatically feeds and distributes the wash-water or liquid over a continuous belt-carried mass or sheet of wool which is to be washed or desinted, such as is disclosed in my prior Patent No. 15 851,539 patented April 23, 1907.

The object of the invention is to provide an apparatus which is capable of a more perfect washing of the wool, and furthermore, to simplify and make less cumbersome 20 the washing machine.

With the above and other objects, which will hereinafter appear, in view, my improved apparatus will now be fully set forth and described, reference being had to the accompanying drawings, which form a part 25 of this specification.

Figure 1 is a side view of the machine, partly in section and partly in elevation. Fig. 2 is a sectional view taken vertically 30 through the tank B, and looking toward the front of the machine. Fig. 3 is a plan view of the front end of the machine, and Fig. 4 is a side elevation of the front end of the machine, showing one of its elements in 35 section.

With more particular reference to said drawings, 1 is an elongated receptacle which is transversely divided into a plurality of compartments or wash-tanks designated respectively as B, C, D, E and F, of which the front and rear tanks, namely B and F respectively, are substantially double the capacity of the remaining or intermediate tanks or compartments. Extending longitudinally of the receptacle 1, over the several wash-tanks, is an endless belt or conveyer 2, which is fed with the extract soaked wool through a chute 3, as indicated by the arrow. Said belt or conveyer 2 is driven 40 from the drive shaft W which is suitably geared to the adjacent supporting roll of said conveyer, and also drives, through an intermediate longitudinal shaft (not visible) and the bevel-gear y, the tensioning roll y'. 45 Squeezing rolls 4 and 5 suitably supported

upon the frame and driven from main drive shaft W are provided to squeeze the mat or sheet of wool to a thinner and drier state upon leaving the machine.

Each of the wash-tanks B, C, D, E and F 50 is filled with the wash liquid to the required height, and conduits S' tapped into the lower parts of said wash tanks are adapted to conduct the fluid from each tank respectively to spray-pipes R, R', R², R³, R⁴, R⁵ and R⁶, each of which is so located transversely of the receptacle 1 that the liquid sprayed therefrom will fall first on the wool and then as a general rule into the same tank or compartment from which it was drawn. 60 Pumps of any suitable type, preferably reciprocating rotary pumps S, as indicated, are located in each conduit and are provided with crank-arms which are severally coupled to a common reciprocating member T having 65 a pivoted connection with a pitman U which is in turn operatively connected to a drive-wheel V mounted on and driven by the main drive shaft W. 70

The spray-pipe R is located over an opening in the chute 3 and delivers the first cleansing liquid to the wool. The spray R' is located practically midway of the compartment or tank B and delivers the second cleansing fluid supply. Spray-pipes R², R³, 85 R⁴ and R⁵ are respectively mounted adjacent the forward wall of the compartment from which the fluid supply was drawn. Spray-pipe R⁶ delivers the last supply of liquid and is located midway over the last or rear compartment F, being connected to any suitable source of unused or supply fluid. 90

When a supply of wool is delivered from chute 3 and is carried toward the rear end of the machine upon conveyer 2 in a mat 95 or sheet, the pumps S are actuated to supply the spray-pipes R—R⁵ with cleansing fluid. It will be evident that the supply from R and R', being the first to pass through the wool and reenter the compartment B, will 100 be most completely saturated with the suinting extracts, while the liquids passing from the succeeding spray-pipes will contain regularly less quantities of the concentrated extracts. Thus the last tank F will be comparatively free from suint or will contain the least concentrated liquid, while each intermediate tank progressively toward tank B will contain a slightly more concentrated liquid. 105

Under conditions depending upon the thickness or depth of the moving mat of material, the grade of the wool, its density or its fatty or unclean condition, the cleansing liquid will soak through the mat with varying speeds, and this circumstance frequently causes the emptying of one of the compartments more rapidly than the companion compartments. That is, the liquid 10 delivered by one spray-pipe, instead of rapidly soaking through and falling into its proper tank or compartment, is carried on and drips into the adjacent rear compartment, which contains a less concentrated 15 liquid, whereas the desired progress of the liquids is toward the foremost tank B, or the one containing the more concentrated fluid, and, likewise, owing also to the irregularities of the wool mat, the progress 20 of the liquid may be too rapid, so that the latter will exceed the desired forward progress, and will empty the tank from which it is drawn too quickly. Graphically described, let the cone a , b , c dependent from the con- 25 veyer 2 over compartment E, represent the drippings caused by fluid delivered at a certain speed upon the mat moving at a corresponding speed for a very short interval. This fluid drips through, first slowly, then 30 with increasing volume, until the height of the cone representing the greatest volume of drippings is reached, after which the volume decreases again until the drippings cease. The length of the base of this cone 35 depends on the density of the mat or any of the other conditions above enumerated, and if the density be great, the liquid will be carried into the zone of the rear adjacent tank before it leaves the mat, or, if the mat 40 is loosely formed, the liquid will pass quickly through the mass and will drip into the tank in front of the one from which the liquid is drawn.

To avoid the continued backward progress 45 of the liquid, and confine the latter to the tank from which it was drawn, or to cause it to progress to the front tank or compartment, it is desirable to start the liquid more or less farther toward the front of the ma- 50 chine, as at a' so that when the point a' in the belt has traveled to a point indicated by c' , the liquid delivered to the mat from the compartment E will have returned to the same compartment or will have dripped into 55 the preceding compartment, according to the position of the deflecting blade, and none of the liquid will have passed into the compartment F. Also, it may be desired to empty a tank entirely of its liquid, or de- 60 liver a large part of its contents into the forwardly adjacent tank. Again referring to the graphic illustration, if the spray is delivered at a fixed point far over the preceding compartment, as at its middle point d , 65 most of the drippings will be received by

said preceding compartment instead of the compartment from which the liquid was drawn, until all has been thus delivered.

The results thus theoretically deduced are practically accomplished as follows:—Piv- 70 otally suspended from suitable brackets 6 located above the spray-pipes R^2 — R^5 are swinging blades or deflectors I , I' , I^2 and I^3 which are positioned to be swung under the spray-openings of the spray-pipes mentioned 75 to deflect the sprays thereof from over their respective normal tanks to the mat above the adjacent forward tank, or tank containing the more concentrated fluid. Automatic means, controlled by the level of the fluid 80 in the said forwardly adjacent tank swings each of said blades or deflectors to cause the latter to deliver the fluid to the mat farther toward the front of the apparatus, the distance varying according to the level in said 85 forward tank. This automatic means is or may be a float, of suitable material as hollow earthenware or glass floated in the preceding tank and having a flexible connection with its proper blade or deflector, to swing the 90 latter as the level of the fluid drops. Said flexible connection may be a wire, rope or similar article passed over a pulley and connected to both the float and the blade. Each float rises and falls with the level of the 95 fluid in its respective tank, and when the fluid is at its normal level, said float snugly seats within a dome-like hood mounted upon the protective grating 8, the flexible connection passing through a centered aperture 100 therein.

The connection between the blades and the floats is such that when the liquids are at their normal levels, the blades or deflectors will be permitted to hang vertically down- 105 ward, so that fluids delivered by the spray-pipes will fall straight down upon the material directly below each pipe. However, when the level in any tank becomes lowered, the float therein descending, draws for- 110 wardly into inclined position the deflector located under the spray-pipe of the rearwardly adjacent tank, with the result that the liquid sprayed therefrom will be directed onto the material of the mat over the next 115 preceding tank, and the distance which the liquid will be deflected depends on the inclination of the blade. Thus, if the liquid in the various tanks or compartments main- 120 tains such a low degree of concentration that it does not affect the automatic draining apparatus hereinafter described to relieve the machine of a too concentrated solution, the deflecting blades will only be affected by the floats to maintain the level in the various 125 tanks by returning the liquid from the rear tanks to the forward tanks, when the progress has been backward, but if the action of the automatic draining apparatus has been such as to rapidly lower the level in the tank 130

or compartment B, then the float in said tank will descend to such a level as to swing the deflecting blade I far over the compartment B, so that the liquid in compartment C 5 will be rapidly emptied into the compartment B by dripping through the mat before the latter reaches the compartment C. This last action, being rapid and continuous, will soon lower the level in the compartment C 10 to such a degree as to effect the float L' in the last named compartment to swing the deflecting blade I', whereby the liquid in compartment D will be passed to compartment C. The same operation will be undergone 15 with regard to the remaining tanks, until the liquid has been uniformly refreshed throughout the apparatus. Thus it will be evident that the level of the liquid in a preceding tank may be restored by the automatic direction thereinto of liquid in the rearwardly adjacent tank, and this apparatus may be used in complete fulfilment of the theoretical action hereinbefore described. When it is desired to empty one or all of the 20 tanks gradually by this action, it is merely necessary to lock in fully deflected position the necessary blades, so that the liquid deflected therefrom will be thrown far over the preceding tank and will consequently trickle 25 into the latter before the moving mat passes thereover.

With the endless conveyer 2 and the flow of the liquids coöperatively regulated, the operation of the apparatus thus far described will be fully apparent.

Automatic means for running off the concentrated liquid from the first tank or compartment B is best shown in Figs. 2, 3 and 4, in which an auxiliary compartment A is 40 cut off from compartment B by a partition 9. Above said compartment or in any other suitable position is suspended a receptacle 10 into which the liquid from the tank B finds its way, said liquid having first been 45 sent through the spray-pipe R and the chute 3 (Fig. 1) to administer the first washing to the wool-mat in said chute. From said receptacle 10 the liquid issues through the pipe 11 into the main portion of compartment A, above the screen 8. A secondary 50 chamber A' is partitioned off from the compartment A by a wall 12, which is spaced along its lower edge from the bottom of the compartment so that the liquid which falls 55 into the main portion of compartment A will pass under said wall and fill said secondary chamber A'. Located in the compartment A, and mounted near the top thereof, as best 60 seen in Figs. 2 and 3, is a channel 13, the latter forming an L across the secondary chamber A' and along the partition 9, so that its short leg overhangs the compartment B. The outer end of the channel 13 is provided with 65 a spout 14, the latter being placed at a point above the bottom of the channel, so that the

liquid must attain a certain level in the channel before it can pass therefrom through said spout 14. Said spout 14 is located over a drain 15, through which the liquid passes to the desired locality for treatment for its 70 potash. The free end of the other or short leg of the channel 13 is provided with a gate-valve 16, by means of which communication with the compartment B is established and regulated. The liquid enters the channel 75 13 through an opening 17 in the wall or partition 9, and its course is determined automatically by the position of the gate-valve 16, above mentioned, said gate-valve being adjusted to open or closed position by 80 the aerometer 18. Said aerometer 18 is connected to the gate-valve 16 by an intermediate pivoted lever 19, and is controlled by the density of the liquid in the chamber A', so that when the said liquid becomes very 85 much concentrated, the aerometer 18 will rise and close the gate-valve 16, more or less. Thus, when the liquid in the compartments A and A' is of normal or working density or in a low state of concentration, the aerometer 90 18 will maintain such a position as to keep the gate-valve 16 open, and the liquid, passing through the opening 17, but not attaining the level of the spout 14, will return to the tank B through the gate-valve 16, and thus be reused in the pipe R. If however, the liquid in chamber A' becomes too concentrated to be used in the spray pipes, the aerometer 18 will rise and automatically 95 close the gate-valve 16, whereby the liquid 100 passing into the channel 13 will rise therein and subsequently pass off into the drain 15. If the rise of the liquid in the secondary chamber A' is for any reason too rapid, it will be passed through the opening 20 into the chamber or compartment B, said opening 20 being placed on a higher level than the opening 17, and constituting a safety outlet.

The various compartments of the machine 110 are cleaned through the man-holes 21, which are shown in dotted lines in Fig. 1, and communication for the purpose of washing the sediments gathered in the compartments A and A' therefrom into the compartment B 115 120 is afforded through the slide-gates 22. Said slide-gates 22 are disposed over openings connecting the compartments A and A' with compartment B at the bottom of the machine, and may be raised or lowered by hand or automatically if desired. The preferred embodiment, as shown in the present structure, is to provide the connecting rods 23 with gear-teeth which mesh with gears carried by a shaft 24, so that the gates may be raised or lowered by means of a hand-wheel 25, also carried by said shaft. As the normal action of the machine is such as to maintain the liquid in the compartments A and A' at a higher level than in the compartment 130

ment B, it is the practice to open the gates 22 just as the machine is shut down, so that the liquid will be caused to rush through the openings thereof, and in restoring the level 5 of the liquid in compartment B, to carry the sediment therewith.

Having thus fully described my invention, what I claim and desire to secure by Letters Patent of the U. S. is—

- 10 1. A wool washing machine, comprising in combination, a plurality of tanks, means for continuously conveying wool thereover, means for projecting the extracting liquid in each tank on the wool at a suitable point, 15 means for abstracting the liquid from one terminal tank whereby the level in the last mentioned tank is lowered and means governed by the lowering of liquid in said last mentioned tank for directing the liquid from 20 the next succeeding tank upon the wool at a point on the wool conveyer ahead of the first named point whereby the last named liquid may leach through the wool into the preceding tank.
- 25 2. A wool washing machine, comprising in combination, a plurality of tanks, means for continuously conveying wool thereover, means for spraying the liquid in each tank on the wool at suitable points, means for 30 automatically exhausting the liquid in one terminal tank as it becomes too highly concentrated, and means adjacent each spraying means and mounted to intercept and deflect the sprayed liquid controlled by the level of 35 the liquid in each preceding tank for restoring the level of said liquid in each said preceding tank by deflecting liquid drawn for said spraying means from each succeeding tank.
- 40 3. A wool washing machine, comprising in combination, a plurality of tanks, means for continuously conveying wool thereover, a plurality of spray-pipes for projecting liquid on the wool disposed over said tanks 45 and each provided with means for drawing liquid from one of said tanks, means for automatically drawing off the highly concentrated liquid from one terminal tank, and a deflecting element located adjacent each of 50 said spray pipes for projecting the liquid

upon the wool at points from which it will leach therethrough into each succeeding tank, and means controlled by the level of the liquid in each said succeeding tank for operating said deflecting elements.

4. A wool washing means, comprising in combination, a plurality of tanks, means for continuously conveying wool thereover, a plurality of spray-pipes for projecting liquid on the wool, disposed over said tanks 60 and each provided with means for drawing liquid from one of said tanks, means for automatically drawing off the highly concentrated liquid from one terminal tank, a swinging, deflecting blade disposed adjacent 65 each of said spray-pipes for varying the point at which the liquid from each spray-pipe will fall upon said wool, means for exhausting the liquid from the terminal tank when said liquid becomes sufficiently concentrated, and means in each tank operatively connected to the deflecting blade adjacent the spray-pipe of each succeeding tank, and controlled by the level of the liquid in said first mentioned tanks whereby 70 said level will be restored from the liquid in said succeeding tanks.

5. A wool washing machine, comprising in combination, a plurality of tanks, means for continuously conveying wool thereover, 80 means for projecting the extracting liquid in each tank on the wool at a suitable point, means for abstracting the liquid from one terminal tank whereby the level in the last mentioned tank is lowered, and means governed by the lowering of the liquid in the last mentioned tank and located to be brought into the path of said extracting liquid at the point of projection thereof for directing the liquid from the succeeding 85 tank upon the wool ahead of the first named point whereby the last named liquid may leach through into the preceding tank.

In testimony whereof I have set hereunto my hand in the presence of two witnesses.

GEORGES MALARD.
